UNITED STATES PATENT OFFICE.

ANDREW Y. McDONALD, OF DUBUQUE, IOWA.

DESIGN FOR A HAND-WHEEL.

SPECIFICATION forming part of Design No. 13,673, dated February 27, 1883.

Application filed January 20, 1883. Term of patent 14 years.

To all whom it may concern:

Be it known that I, ANDREW Y. McDONALD, a citizen of the United States, residing at Dubuque, in the county of Dubuque and State of Iowa, have invented and produced a new and original Design for Hand-Wheels, of which the following is a full, clear, and exact description.

Reference is to be had to the accompanying drawing, forming part of this specification, in which the figure represents a face view of my newly-designed hand-wheel.

My new and improved design is more especially intended to be applied to the hand-wheels of globe and other valves, such as are used for controlling the flow of steam, water, and other gases or fluids. Heretofore such hand-wheels have been made which presented various configurations on their rims or peripheral portions, including bullet or knob like ornaments, knobs, and scallops arranged either in close proximity to each other or at different distances apart around the rim of the wheel.

The leading feature of my design consists in a "struck-up" corrugated surface for the rim of the wheel, the outlines of which, when viewed from the face side of the wheel, give the appearance of one or more ropes or cords wound spirally around a circular core.

A is the hub of the wheel, and B its arms,

both of which may be of any desired configuration. C is the rim or peripheral portion of the wheel, of circular contour, both facially and in its transverse section, and ornamented by close and spirally-arranged continuous corrugations of convex form externally transversely to their length, thus presenting to the eye the appearance of one or more ropes or cords wound spirally around a circular core. The drawing represents two of such spirally-arranged continuous corrugations or rope-like ornamentations, b c, disposed intermediately of each other all around the rim of the wheel.

I claim—

1. The design for a hand-wheel, herein shown and described, the same consisting of one or more close and spirally-arranged continuous corrugations on the rim of the wheel, resembling one or more round ropes wound spirally around the rim.

2. The design for a hand-wheel, herein shown and described, the same consisting of a rim, C, of circular contour both facially and transversely, and ornamented by duplicate endless intermediately and spirally arranged corrugations, b c, resembling ropes or cords.

ANDREW Y. McDONALD.
